UNITED STATES PATENT OFFICE.

LOUIS A. SUEKOFF, OF CHICAGO, ILLINOIS.

SPRING CUSHION CONSTRUCTION.

1,411,227.

Specification of Letters Patent. Patented Mar. 28, 1922.

Original application filed January 30, 1919, Serial No. 273,957. Divided and this application filed June 11, 1920. Serial No. 388,108.

To all whom it may concern:

Be it known that I, LOUIS A. SUEKOFF, a citizen of the United States, residing at Chicago, in the county of Cook and State of Illinois, have invented certain new and useful Improvements in Spring Cushion Constructions, of which the following is a specification.

This invention relates to improvements in 10 spring cushion constructions adapted for incorporation in seat and mattress structures, and the present application is a division of my former application which has issued as Letters Patent of the United States No. 15 1,397,021, dated November 15, 1921.

The object of the present invention is to provide a construction of this character wherein maximum economy may be effected in the amount of materials employed when 20 producing the same.

Furthermore, the invention also contemplates the provision of a novel form and arrangement of the spring units and their envelopes, whereby but a single ply of material 25 is present between contiguous springs, thus eliminating unnecessary use of the fabric of the envelopes and at the same time providing the requisite separation of the springs to prevent their contact with each other. The 30 sound of the springs in their relative movement with respect to each other is thereby precluded, while material saving in the textile fabric of the envelopes or covering for the springs is effected.

35 Other objects and advantages will appear as the nature of the improvements is better understood, the invention consisting substantially in the novel construction, combination and arrangement of parts hereinafter 40 fully described, illustrated in the accompanying drawings, and finally pointed out in the appended claims.

In the drawings—

45 Fig. 1 is a top plan view of the herein-described invention, the springs being illustrated in dotted lines.

Fig. 2 is a detail vertical transverse sectional view on the line 2—2, Fig. 1.

50 Fig. 3 is a similar view on the line 3—3, Fig. 1.

Fig. 4 is a fragmentary perspective view, parts being broken away, of the herein-described cushion construction, the springs being omitted.

55 Referring now in detail to the accompany-

ing drawings, it will be observed that the herein described spring cushion construction includes a plurality of individual springs properly separated from each other to prevent contact of the several springs so that 60 they may move independently, and likewise without the metallic sound that emanates from the rubbing action of their coils upon each other. The particular form illustrated embodies a top layer 10 and a 65 bottom layer 11, which layers preferably are formed of textile fabric, and said layers constitute the top and bottom or face portions of the cushion construction. Obviously, the dimensions of these layers are such as are 70 required to be included in the finished product. Arranged between the top and bottom layers 10 and 11, and extending across one dimension thereof, is a series of continuous 75 division walls or partitions 12, which partitions are parallel to each other and spaced apart the required distance, and their upper and lower edges are connected, as at 13, to the layers 10 and 11. This is effected preferably by stitching, but other equivalent 80 fastenings may be employed. Arranged at right angles to the continuous partitions 12 is a plurality of division walls or partitions 14, each of which is formed of an unbroken web of material. These are only sufficiently 85 wide to extend between the continuous walls or partitions 12, and their upper and lower ends 15 are connected permanently to the top and bottom layers 10 and 11, respectively, as by stitching 16 or its equivalent. 90 These walls or partitions 14 are spaced from each other a sufficient distance to provide the desired size of spacing or pocket, and in each of these pockets is positioned a 95 coil spring 17.

From the foregoing description it will be observed that there is but a single ply of material between the contiguous springs 17, and the latter are thus separated by the minimum amount of material without, however, losing the advantages of preventing the coils of the contiguous springs contacting with each other in their relative movement. The rubbing of the contiguous springs, therefore, is precluded, and the noise 105 arising from the usual metallic contact of the springs is wholly eliminated.

The top 10 and the bottom 11 are of the necessary dimension, as previously indicated, to conform to the desired size of the 110

finished cushion. The upper and lower edges of the continuous partitions 12 and of the short division walls or partitions 14 only are connected to said top and bottom. 5 This leaves the edges of the division walls or partitions 14 wholly disconnected from the contiguous continuous walls 12, the free edges of the division walls 14 and the continuous walls 12 cooperating to form openings at the corners of the pockets, thus enabling ready access to be had to the several pockets for introduction and removal of the respective springs to and from these pockets. The ends of the springs bear 10 against the top 10 and bottom 11 and require no connection therewith, the expansive force of the springs distending the fabric of the cushion structure, and thereby placing the walls 12 and 14 under tension. 15 The springs thus are freely displaceable, and as no fastenings are required for holding the springs in place they may be quickly introduced to and positioned within their respective pockets when assembling 20 the cushion construction.

A significant feature of the herein-described structure is the fact that but a single ply of material is required to separate the several springs from each other, and 25 this economizes in the amount of material employed in forming the division walls.

It will be observed further that the openings at the corners of the pockets are aligned in the direction of the continuous walls 12, 30 thus permitting the springs of all the pockets between each pair of continuous walls to be introduced simultaneously thereto for positioning therein, as by the use of the inserting tool made the subject of Letters 35 Patent No. 1,352,157 granted to me September 7, 1920. These openings enable such tool readily to be guided and passed into the pockets for discharge thereinto from the tool of the several springs carried thereby. 40 This effects filling of the springs into the several pockets in a most rapid and efficient manner.

I claim:

1. A spring cushion construction of the 45 class described, comprising a top, a bottom spaced therefrom, a plurality of continuous spaced partitions arranged between said top and bottom and connected thereto at their upper and lower edges, a plurality of division walls arranged in the spaces be-

tween said continuous partitions and extending at right angles to the latter to divide said spaces into a plurality of pockets, each of said division walls being formed of an unbroken web the ends of which are 60 connected permanently to said top and bottom and the side edges of which are free, and a plurality of springs arranged in said pockets, the free edges of said division walls and the continuous partitions co-operating 65 to form openings through which said springs may be guided and passed into said pockets when positioning the springs in the latter.

2. A spring cushion construction of the 70 class described, comprising oppositely disposed layers constituting the face portions of the cushion and spaced apart a predetermined distance to accommodate therebetween the resilient elements of the cushion, 75 a series of continuous parallel spaced partitions arranged between said layers and extending across one dimension thereof, said partitions being connected along their opposite edges to said layers, a plurality of 80 division walls arranged across the spaces between said continuous partitions and dividing the latter into a series of pockets each of which receives one of the resilient elements of the cushion, each of said division walls being formed of an unbroken web connected permanently along its ends to said oppositely disposed layers, and a 85 plurality of springs arranged in said pockets, said division walls being free at their 90 edges from connection with the continuous partitions and co-operating with the latter to form openings through which said springs may be guided and passed into said pockets when positioning the springs in the 95 latter, said openings being located at the corners of the pockets and aligned in the direction of the continuous walls, whereby the springs of all the pockets between each 100 pair of continuous walls may be introduced simultaneously thereto for positioning therein.

In testimony whereof I have hereunto signed my name in the presence of two subscribing witnesses.

LOUIS A. SUEKOFF.
